(57) **CLAIM**

The ornamental design for an auxiliary lens mounting part, as shown and described.

DESCRIPTION

FIG. 1 is a front elevational view of an auxiliary lens mounting part showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof, the broken lines are for illustrative purposes only and form no part of the claimed design;

FIG. 8 is a perspective view thereof;

FIG. 9 is a perspective view thereof;

FIG. 10 is a perspective view thereof; and,

FIG. 11 is a perspective view thereof.

The broken line showing of the human form is for illustrative purposes only and forms no part of the claimed design.
